UNITED STATES PATENT OFFICE.

LOUIS REISFIELD, OF CHICAGO, ILLINOIS, ASSIGNOR TO J. W. HOODWIN COMPANY, OF CHICAGO, ILLINOIS, A CORPORATION.

DESIGN FOR A PUNCH-BOARD.

55,817.

Specification for Design.

Patented July 13, 1920.

Application filed April 10, 1920. Serial No. 373,009. Term of patent 14 years.

To all whom it may concern:

Be it known that I, LOUIS REISFIELD, formerly a subject of the King of Hungary, residing at Chicago, in the county of Cook and State of Illinois, have invented a new, original, and ornamental Design for Punch-Boards, of which the following is a specification, reference being had to the accompanying drawing, forming part thereof.

The figure is a plan view of a punch-board, showing my new design.

I claim:

The ornamental design for a punch-board, as shown.

LOUIS REISFIELD.
